(57) **CLAIM**

The ornamental design for an illuminated light, as shown and described.

DESCRIPTION

FIG. 1 is a perspective view of an illuminated light according to a first embodiment of the invention.

FIG. 2 is a front view of an illuminated light according to an embodiment of the invention.

FIG. 3 is a rear view of an illuminated light according to an embodiment of the invention.

FIG. 4 is a right side view of an illuminated light according to an embodiment of the invention. The left side view of an illuminated light according to an embodiment of the invention is a mirror image of the right side view illustrated in FIG. 4.

FIG. 5 is a top view of an illuminated light according to an embodiment of the invention. The top view of an illuminated light according to an embodiment of the invention is identical to the top view illustrated in FIG. 5.

Features shown with broken lines in the figures described below form no part of the design to be patented.
